UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

GUN.

1,303,336.

Specification of Letters Patent. Patented May 13, 1919.

Application filed April 12, 1918. Serial No. 228,105.

To all whom it may concern:

Be it known that I, CHARLES F. LEFEVER, a citizen of the United States of America, residing at Plymouth, in the county of 5 Wayne and State of Michigan, have invented certain new and useful Improvements in Guns, of which the following is a specification, reference being had therein to the accompanying drawings.

10 The invention relates to a gun of the type in which air is compressed to eject the projectile. One of the objects of the invention is to obtain a construction in which the tube containing the projectile is removably engageable with the barrel of the gun and forms a cylinder within which air is compressed for ejecting the projectile. Another object is to obtain means for ejecting the tube and for safe-guarding the manipulator 15 20 25 30 35 40 45 50 55 60 65 70 75 80 85 90 95 100 105 110

is secured to the clip F and to the rear end of the stock A and the locking bolt G having the laterally-extending handle G' rigidly mounted upon its rear end, is slidably mounted within the barrel B.

The barrel B is provided in its upper portions with the elongated aperture H through which the tube I may be inserted into the barrel and with the elongated slot H' having 65 at its forward end a laterally-extending recess H² which slot and recess are slidably engaged by the guide J upon the locking bolt G. The strap B' for reinforcing the barrel B is connected to the outer sides 70 thereof and extends over the slot H', sufficient clearance being provided for the passage of the guide J along the slot. The locking bolt G is hollow and has its forward end rigidly secured to the cylinder K which has 75 an outer diameter such that it slidably fits within the annulus K' within the barrel B and has an inner diameter equal to the inner diameter of the tube I.

For positioning the tube within the barrel 80 B, the cylinder K has the tapering forward end K² which is adapted to engage the outwardly flaring end I' of the tube I. The barrel B is provided with the annulus L located forward of the aperture H and having 85 its rear end L' tapering. The tube I has its forward end I² of reduced diameter which end slidably engages the tapering end L' and is positioned thereby, the forward movement of the tube being limited by the 90 shoulder I³ contacting with the tapering end L'. The projectile M is made of yieldable material, such as rubber or cork, and when inserted into the tube I, engages the inner wall of the reduced end I² to make therewith 95 an air-tight seal.

For ejecting the projectile M from the tube I, the following construction is provided: N is a plunger slidably engaging the inner walls of the cylinder K and adapted 100 to slidably engage the inner walls of the tube I. This plunger is rigidly connected to the rod N' extending rearwardly within the locking bolt G, this rod in turn being rigidly connected at its rear end to the transversely-extending and depending detent member O having the detent O'. Connected 105 to the lower end of the detent member O is the forwardly-extending rod P substantially parallel to the rod N'. The rod P extends 110 through the strap Q connecting the forward ends of the depending side plates C' and

In the drawings:

Figure 1 is a side elevation of the gun;

30 Fig. 2 is a longitudinal sectional view therethrough with the tube for containing the projectile removed;

Fig. 3 is a similar view with the tube for containing the projectile in place within the 35 barrel of the gun;

Fig. 4 is a traverse sectional view on the line 4—4 of Fig. 3;

Fig. 5 is a sectional view through the plunger.

40 A is the stock of the gun having the hand portion A', B the barrel, C the trigger, C' the side plates on opposite sides of the trigger and depending from the barrel, D the trigger guard, and E and E' are, respectively, the rear and forward sights mounted upon the barrel. For securing the barrel B to the stock A and its hand portion A' the clip F is provided surrounding and slidably engaging the forward ends of the barrel and

50 the hand portion and the screw D' is provided threadedly engaging the strap C² connecting the depending side plates. The screw also secures the forward end of the trigger guard D to the hand portion.

55 For the purpose of further giving the gun the appearance of an army rifle the strap F'

has at its forward end the transversely-extending member P'. A coil spring Q' is provided surrounding the rod P and abutting against the strap Q and the transversely-extending member P'. The hand portion A' of the stock forms the housing for inclosing the spring. The locking bolt G has the longitudinal slot G² in its lower portion through which the detent member O passes; the slot extending from the rear end of the locking bolt to the cylinder K. For engaging the detent O' the sear R is provided pivoted at R' upon the depending side flanges C' of the barrel B. The spring S engaging a recess in the stock A and also engaging a rear projection R² upon the sear R yieldably forces the same forward and upward to engage the detent O' when the latter is moved back sufficiently far. The trigger C also pivoted at R' is adapted to disengage the sear R from the detent O' thereby permitting of the rapid forward movement of the plunger N through the stored power in the spring Q'.
 25 In order to eject the tube I, the ejector rod S' is provided pivoted at S² upon the barrel B and extending through the slot T in the lower portion of the barrel. Between the outer end of the ejector rod S' and the lower side of the barrel B is the coil spring T' which yieldably normally forces the opposite or inner end upward through the slot T so that upon removing the cylinder K from the rear end of the tube I, the ejector rod S' is free to force the tube out of engagement with the barrel. The ejector rod also performs the function of safeguarding the manipulator of the gun when the tube is removed, since the spring T' yieldably normally holds the forward end of the ejector rod S' in the path of movement of the plunger N so that the latter can not move into the space left vacant by the cartridge. In order to prevent the lateral disengagement of the ejector rod S' from the plunger N, the plunger is made cup-shaped with the forwardly-extending flanges U so that if the ejector rod S' were moved downward, its contacting end would engage with the lower forwardly-extending flanges of the plunger and would be prevented from moving farther.
 55 In operation, assuming the parts to be in position, as shown in Fig. 3, the gun is in condition to be fired by pulling the trigger C which permits of the forward movement of the plunger N into the tube I under the stored power in the spring Q'. To eject the tube I the locking bolt G is drawn backward thereby drawing the tapering end K² of the cylinder K out of engagement with the flared end I' of the tube I and also the plunger N out of the tube, thereby permitting of the upward movement of the inner end of the ejector rod S' to force the tube

out of the barrel. The plunger N is withdrawn by means of the lower forward end G³ of the locking bolt G contacting with the detent member O. Upon further backward movement of the locking bolt the detent O' is engaged by the sear R and the spring Q' is placed under greater compression. 70

A tube with its projectile can now be placed into the barrel B by forcing the inner end of the ejector rod S' downward and this 75 tube is positioned by moving the locking bolt G forward with its guide J engaging the slot H' when the cylinder K engages the tube I so that both the forward and rear ends of the tube are positioned. By rotating the locking bolt G to place the guide J in the laterally-extending recess H² the tube is locked in position and the gun is in condition to be again fired. 80

When the tube I is not in place, the inner 85 end of the ejector rod S' is in the path of movement of the plunger N so that the latter can not move into the tube space when the gun is uncocked. Furthermore the ejector rod S' can not be forced out of engagement until the plunger N is moved backward due to the flanges U upon the plunger N. To assist in giving the gun the appearance 90 of an army rifle, the tube I is made to look like a cartridge and is adapted to receive the projectile before insertion into the barrel of the gun. 95

From the above description it will be readily seen that a gun is provided which has the appearance of an army rifle and is 100 safe to operate either when the tube is in or out of place. Furthermore, it is seen that the tube forms the cylinder for the compressed air and is positioned within the gun so that the plunger will easily engage 105 the tube. 105

What I claim as my invention, is:

1. In a gun provided with a barrel, a tube simulating a cartridge, insertible into the barrel of the gun to form an element of the 110 air compression chamber.

2. In a gun provided with a barrel, a tube simulating a cartridge and adapted to receive a projectile, said tube with the projectile insertible into the barrel of the gun and forming 115 a chamber for compressed air.

3. In a gun provided with a barrel, a tube simulating a cartridge and having a seat for a projectile, said tube with the projectile engageable with and removable from the barrel of the gun, and means for compressing air within said tube to eject the projectile. 120

4. In a gun provided with a barrel, a tube simulating a cartridge and insertible into the barrel of the gun, and a plunger movable within said tube for compressing air. 125

5. In a gun, the combination with a barrel, of a tube, means for compressing air within said tube, and means for ejecting said tube from said barrel. 130

6. In a gun, the combination with a barrel, of a tube engageable therewith, an ejector rod projecting through the under side of said barrel, and a spring for normally holding one end of said ejector rod in said barrel. 5
7. In a gun, the combination with a barrel, of a tube engageable therewith, a plunger slidably engaging said barrel and adapted to slidably engage said tube, and means 10 for limiting the movement of said plunger when said tube is disengaged from said barrel.
8. In a gun, the combination with a barrel, of a tube engageable therewith, a plunger slidably engaging said barrel, and a common means for ejecting said tube and 15 for limiting the movement of said plunger after the tube is ejected.
9. In a gun, the combination with a barrel, of a plunger slidably engaging said barrel, means for contacting with said plunger to limit its movement in one direction, and means for preventing the disengagement 20 of said contacting means from said plunger.
10. In a gun, the combination with a barrel, of a plunger slidably engaging said barrel, a rod mounted on said barrel and adapted to contact with said plunger, said 25 plunger having an outwardly projecting flange for preventing the lateral disengagement of said rod from said plunger.
11. In a gun, the combination with a barrel, of a tube simulating a cartridge and 30 insertible into said barrel, means for positioning said tube within said barrel, and means for compressing air within said tube. 35
12. In a gun, the combination with a barrel, of a tube engageable therewith, a locking bolt engageable with one end of said tube for positioning the same within said barrel, and a plunger for compressing air within said tube. 40
13. In a gun, the combination with a barrel, of a tube having a flared end, a hollow locking bolt engageable with said flared end for positioning the same relative to said barrel, a plunger slidably engaging the walls of said locking bolt and tube for compressing air within the latter. 45
14. In a gun, the combination with a barrel having a portion of reduced diameter, of a tube engageable with said barrel and having a reduced end portion engageable with said barrel portion of reduced diameter. 50
15. In a gun, the combination with a barrel, of a plunger therewithin, a plunger rod, a detent member rigidly connected to said plunger rod, a second rod directly connected 55 to said detent member, a coil spring surrounding said second rod, and trigger mechanism engaging said detent member.
16. In a gun, the combination with a barrel, of a tube laterally insertible into said barrel and forming an element of an air compression chamber. 60
17. In a gun, the combination with a barrel having an aperture in its wall, of a tube insertible into said barrel through said aperture. 65

In testimony whereof I affix my signature.

CHARLES F. LEFEVER.
